UNITED STATES PATENT OFFICE

WILLIAM G. SHELTON, OF ST. LOUIS, MISSOURI

HAIR WAVING DEVICE

Application filed January 5, 1931. Serial No. 506,768.

My invention relates to the hair waving art and consists in a novel heater and hair gripping means for use with a curling rod and clamp such as is described in Patent No. 5 1,778,870, issued to me.

Heaters, such as are now in use in permanent waving human hair, frequently are provided with a pair of hair clamping arms, each having a hair gripping jaw on one end 10 and manipulating handles therefor, and additional elements for mounting the jaws, thrusting them together and maintaining the heater in engagement with a coil of hair or a supply pad surrounding it.

15 The main object of my present invention is to provide a simpler and lighter heater than has heretofore been produced, in which the hair clamping arms and jaws as well as the spring retaining element are included in a 20 single piece of metal to which are secured the manipulating handles. I attain this object and others referred to hereafter by the structure illustrated in the accompanying drawings in which—

25 Figure 1 is a side view of my improved heater.

Figure 2 is a vertical transverse section taken substantially on line 2—2 of Figure 1.

Figure 3 is a horizontal section taken on 30 line 3—3 of Figure 1.

My device includes an arcuate heater body having an open side and including an inner wall 1 and an outer wall 2 between which a heating unit of any suitable design may be placed. A longitudinal offset depression 3 is formed in the upper portion of the outer wall 2 and a handle mounting element 12 is mounted upon this depressed portion by bolts 13. Member 4 is composed of a sheet of spring 35 metal shaped to conform in general with the contour of the outer wall 2 of the heater body and its ends are bent towards each other to form hair gripping jaws 5 which, in the normal position, extend partially across the open 40 side of the heater.

The spring member 4 has bosses 6 formed therein at each side and a manipulating handle 7 is secured to each boss by means of rivets

45 8. Each handle 7 has a projection 9 on its inner side which is adapted to bear against

the member 4. When the upper ends of the handles 7 are pressed towards each other the projections 9 engage the member 4 and co-operate with the securing rivets 8 to distort the spring and retract the gripping jaws 5 55 from their normal position beneath the heater.

A block 12 is mounted in the middle of the member 4 above its point of contact with the heater and the assembly is maintained by 60 bolts 13 which extend through the upper wall 2 of the heater body, the spring member 4, and the block 12. The bolt holes in the block are countersunk at the top to provide for nuts 14. Terminal prongs 15, projecting 65 from the block 12, are adapted to fit into corresponding holes in a terminal plug 16 to connect the heater with a source of current.

In the permanent waving operation, a strand of hair, previously segregated, is 70 clamped between the jaws 17 and 18 of a protector clamp device and then wrapped around the curling rod 11 and a moistened supply pad 10 is applied to the coil. The heater jaws are then opened and the heater 75 applied to the curl. When the manipulating handles are released, the jaws will grip the hair strand or the supply pad 10, as shown in Figure 2, and hold the heating unit in snug engagement with the curl.

80 The improved heater described is simple and sturdy of construction and has fewer parts and less weight than previous devices. These features contribute towards lowering the cost of the heater and add to the convenience and comfort of the operator and customer. Obviously, the structure illustrated and described may be modified as to various details without departing from the spirit of the invention and I contemplate the exclusive 85 use of all such variations as come within the scope of my claims.

I claim:

1. In a hair waving device, a heater, and a unitary member mounted thereon and including converging hair gripping jaws at each end and an intermediate spring portion.

2. In a hair waving device, a heater, and a member mounted thereon, said member com-

- prising a single piece of metal having its ends bent towards each other to form hair gripping jaws and having an intermediate resilient portion.
5. 3. In a hair waving device, a heater, and a member mounted thereon, said member comprising a single piece of metal having its ends bent towards each other to form hair gripping jaws and having an intermediate spring portion of arcuate contour.
4. In a hair waving device, a heater including an outer wall, a projection in the middle of the upper portion thereof, and a spring member mounted on said projection and having its ends bent towards each other to form hair gripping jaws.
- 15 5. In a hair waving device, a heater having an open side, a depression in the middle of the upper wall of said heater, and a spring member mounted on said depression and having its ends bent towards each other to form hair gripping jaws extending across said open side.
- 20 6. In a hair waving device, a heater, a unitary spring member mounted thereon and including converging hair gripping jaws and an intermediate arcuate portion, and a pair of manipulating handles secured to said member.
- 30 7. In a hair waving device, a heater, a spring member mounted thereon comprising a single piece of metal having its ends bent towards each other to form hair gripping jaws and having an intermediate resilient portion of arcuate contour, there being flattened portions in said member spaced from the center thereof, and manipulating handles mounted on said portions.
- 40 8. In a hair waving device, a heater, a spring member mounted thereon comprising a single piece of metal having its ends bent towards each other to form hair gripping jaws and having an intermediate resilient portion of arcuate contour, and manipulating handles attached to said member at each end of said arcuate portion, each handle having a boss spaced from its point of attachment with said member and adapted to engage said member when said handles are pressed together to open said jaws.
- 45 9. In a hair waving device, an arcuate heater having an open side adapted to receive a hair wound curling rod, and a member mounted on said heater, said member having its ends bent across said open side to form hair gripping jaws and having an intermediate resilient portion of arcuate contour conforming in general with the contour of the outer wall of said heater.
- 55 10. In a hair waving device, a heater having an open side, a sheet spring mounted thereon and having its ends extending partially across said open side to form jaws and having an intermediate arcuate portion, a connection receiving block mounted on said
- 85 90 95 100 105 110 115 120 125 130
- spring adjacent its point of contact with said heater, and securing means extending through the upper wall of said heater, said spring, and said block.
11. In a hair waving device, a heater having an open side, a spring member mounted thereon and having its ends extending across said open side to form hair gripping jaws, a connection receiving block mounted on said spring member adjacent its point of contact with said heater, and manipulating handles adapted to be pressed together to open said jaws.
- In testimony whereof I hereunto affix my signature this 29th day of December, 1930.
- WILLIAM G. SHELTON.
